UNITED STATES PATENT OFFICE.

BENJAMIN PHILLIPS, OF CINCINNATI, OHIO.

DESIGN FOR AN OIL-DISPENSING CABINET.

Application filed December 30, 1925. Serial No. 15,302. Term of patent 7 years.

To all whom it may concern:

Be it known that I, BENJAMIN PHILLIPS, a citizen of the United States, residing at Cincinnati, in the county of Hamilton and State of Ohio, have invented a new, original, and ornamental Design for an Oil-Dispensing Cabinet, of which the following is a specification, reference being had to the accompanying drawing, forming part thereof.

The figure is a perspective view of the oil dispensing cabinet showing my new design.

I claim:

The ornamental design for an oil dispensing cabinet as shown.

BENJAMIN PHILLIPS.
